Primary Examiner—Robin V. Taylor(74) **Attorney, Agent, or Firm**—Browning Bushman**CLAIM**

The ornamental design for a waste treatment plant, as shown and described.

DESCRIPTION

FIG. 1 is a top, elevational view of the waste treatment plant of the present invention;
FIG. 2 is a front, elevational view of the waste treatment plant of FIG. 1;
FIG. 3 is a rear, elevational view of the waste treatment plant of FIG. 1;
FIG. 4 is a bottom, plan view of the waste treatment plant of FIG. 1;
FIG. 5 is a side, elevational view of the waste treatment plant of FIG. 1; and,
FIG. 6 is an opposite side, elevational view of the waste treatment plant of FIG. 1.
